US00D629774S

(12) **United States Design Patent**
Kim et al.

(10) **Patent No.:** **US D629,774 S**
(45) **Date of Patent:** ** *Dec. 28, 2010

(54) **MOBILE PHONE**

(75) Inventors: **Jin-Soo Kim**, Yongin-si (KR);
Min-Hyouk Lee, Seoul (KR);
Seog-Guen Kim, Seoul (KR)

(73) Assignee: **Samsung Electronics Co., Ltd.** (KR)

(*) Notice: This patent is subject to a terminal disclaimer.

(**) Term: **14 Years**

(21) Appl. No.: **29/345,485**

(22) Filed: **Oct. 16, 2009**

(30) **Foreign Application Priority Data**

Sep. 14, 2009 (KR) 30-2009-0040758

(51) **LOC (9) Cl.** **14-03**

(52) **U.S. Cl.** ..... **D14/138 AD**
